CLAIM

The ornamental design for a vibrator, as shown and described.

DESCRIPTION

FIG. 1 is a perspective view of a vibrator showing my present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the vibrator which form no part of the claimed design.

The waved lines shown in the middle portion of the vibrator indicate the appearance of any portion of the article between the break lines forms no part of the claimed design.
